(57) **CLAIM**

The ornamental design for an ear bud adapter, as shown and described herein.

DESCRIPTION

FIG. 1 is a front perspective view of an ear bud adapter showing our new design.

FIG. 2 is a rear perspective view thereof;

FIG. 3 is a front perspective view thereof;

FIG. 4 is a rear elevational view thereof;

FIG. 5 is a side elevational view thereof; and,

FIG. 6 is an opposite side elevational view thereof;

FIG. 7 is a top plan view thereof; and,

FIG. 8 is a bottom plan view thereof.

The broken lines form no part of the claimed design.
